(57) **ABSTRACT**

A fuse element is a fuse element (1) including a flat plate-shaped blowout section (1e) with no through-hole disposed between a first terminal (20a) and a second terminal (20b), in which a width (1d) of the blowout section (1e) has a length equal to or greater than 80% of a width (2d) of each of joining portions joining the first terminal (20a) and the second terminal (20b) to the blowout section (1e). The width (1d) of the blowout section (1e) is preferably a length equal to or greater than 95% of the width (2d) of each of the joining portions.

FUSE ELEMENT, FUSE DEVICE, AND PROTECTION DEVICE

PRIORITY APPLICATIONS

This application is a U.S. National Stage Filing under 35 U.S.C. § 371 from International Application No. PCT/JP2020/030803, filed on Aug. 13, 2020, and published as WO2021/039426 on Mar. 4, 2021, which claims the benefit of priority to Japanese Application No. 2019-152939, filed Aug. 23, 2019; the benefit of priority of each of which is hereby claimed herein, and which applications and publication are hereby incorporated herein by reference in their entireties.

TECHNICAL FIELD

The present invention relates to a fuse element, a fuse device, and a protection device.

BACKGROUND ART

A fuse device is known as a current cutoff element that cuts off a current path in a case where an overcurrent exceeding a rated current flows through a circuit board. In such a fuse device, a fuse element is blown out due to heat generation caused by an overcurrent to cut off the current path.

For example, Patent Document 1 describes a fuse including a fuse element that has terminal sections on both sides of a blowout section, and a casing that surrounds the blowout section, and the blowout section is provided with a notch or a plurality of small holes.

Patent Document 2 describes a chip-type fuse in which a fuse positioned between two flat plate-shaped sections is formed integrally with the two flat plate-shaped sections. Patent Document 2 describes the chip-type fuse in which connecting sections are formed at both ends of a fuse body, and a long edge of the connecting sections is longer than a width dimension of the fuse body.

A protection device using a heat-generating element (heater) is known as a current cutoff element that cuts off a current path in a case where an abnormality other than the occurrence of an overcurrent occurs in a circuit board. In the protection device, a fuse element is blown out due to heat generated by the heat-generating element. The heat-generating element generates heat with a current flowing therethrough at the time of an abnormality other than the occurrence of an overcurrent.

SUMMARY OF INVENTION

Technical Problem

In recent years, an increase in a rated current has been required in fuse devices and protection devices.

In a high-rated fuse device of the related art, as a material of the fuse element, a high-melting-point metal, such as copper (melting point 1085° C.), is used. In a fuse element composed of a high-melting-point metal, such as copper, a heat-generating point where heat is locally generated is formed in a blowout section. With this, excessive heating of the terminal coupled to the blowout section of the fuse element can be prevented, such that an electronic apparatus to which the fuse device is attached does not exceed a heat resistance temperature. For example, in an electronic apparatus that forms electrical connection using solder, the heat resistance temperature is about 220° C.

The heat-generating point in the fuse element is formed by providing a plurality of small holes in the blowout section or by thinning the width of the blowout section. For example, Patent Document 1 describes the fuse element in which the blowout section is provided with the notch or a plurality of small holes. Patent Document 2 describes the chip-type fuse in which the long edge of the connecting sections is longer than the width dimension of the fuse body.

In the fuse element composed of a high-melting-point metal, such as copper, there is a need to secure a distance between the heat-generating point and each of the terminals coupled to the blowout section such that the terminal is not excessively heated due to heat from the heat-generating point. This is a factor that obstructs a reduction in size in a fuse device having a large rated current as will be described below.

In a fuse element disposed between two terminals, a length (a length between the two terminals) of the fuse element and a resistance value are in a proportional relationship. Accordingly, in a case where the fuse element is extended to increase a distance between the heat-generating point and each of the terminals, such that excessive heating of the terminal is prevented, the resistance of the fuse element increases. For this reason, it is difficult to increase the rated current of the fuse device including the fuse element.

In order to increase the distance between the heat-generating point and each of the terminals coupled to the blowout section and to suppress an increase in resistance of the fuse element, it may be available to increase the cross-sectional area of the blowout section. However, in a case where the cross-sectional area of the blowout section increases and the resistance of the fuse element decreases accordingly, the amount of heat of the heat-generating point increases. As a result, the distance between the heat-generating point and each of the terminals should be further increased to suppress overheating of the terminal.

From this, in the fuse device including the fuse element that is composed of a high-melting-point metal, it is difficult to achieve both a reduction in size of the fuse device and an increase in rated current.

The invention has been accomplished in view of the above-described situation, and an object of the invention is to provide a fuse element capable of contributing to an increase in rated current and a reduction in size of a fuse device and a protection device.

An object of the invention is to provide a fuse device and a protection device including the fuse element, capable of contributing to an increase in rated current and a reduction in size.

The invention provides the following means to solve the above-described problem.

(1) A fuse element includes a flat plate-shaped blowout section with no through-hole disposed between a first terminal and a second terminal, in which a width of the blowout section has a length equal to or greater than 100% of a width of each of joining portions joining the first terminal and the second terminal to the blowout section.

(2) In the fuse element described in (1) above, a blowout temperature of the blowout section may be 140° C. to 400° C.

(3) In the fuse element described in (1) or (2) above, the blowout section may be formed in such a manner that a low-melting-point metal layer and a high-melting-point metal layer having a melting point higher than the low-melting-point metal layer are laminated in a thickness direction.

(4) In the fuse element described in (3) above, the low-melting-point metal layer may be composed of Sn or an alloy containing Sn as a primary constituent, and the high-melting-point metal layer may be composed of any one selected from Ag, Cu, an alloy containing Ag as a primary constituent, and an alloy containing Cu as a primary constituent.

(5) In the fuse element described in (3) or (4) above, the blowout section may be composed of the low-melting-point metal layer and the high-melting-point metal layers laminated on both surfaces of the low-melting-point metal layer.

(6) In the fuse element described in (5) above, side surfaces of the blowout section on each side joining to the first terminal and the second terminal may be coated with high melting-point metal layer.

(7) In the fuse element described in any one of (1) to (6) above, the width of the blowout section may be a length equal to or less than 200% of the width of each of the joining portions.

(8) In the fuse element described in any one of (1) to (7) above, the blowout section may be joined to the first terminal and the second terminal by a conductive connection member.

(9) A fuse device includes the fuse element described in any one of (1) to (8) above.

(10) In the fuse device described in (9) above, the first terminal and the second terminal may be disposed on a front surface of an insulating substrate.

(11) A protection device includes the fuse element described in any one of (1) to (8) above, and a heat-generating element configured to heat the fuse element to be blown out, in which the first terminal and the second terminal are disposed on an insulating substrate, and the fuse element is disposed across the first terminal and the second terminal.

Advantageous Effects of Invention

The fuse element of the invention can contribute to an increase in rated current and a reduction in size in the fuse device and the protection device including the fuse element.

The fuse device and the protection device of the invention include the fuse element of the invention, and can thus contribute to an increase in rated current and a reduction in size.

FIG. 1(a) is a plan view showing a fuse device of a first embodiment, and FIG. 1(b) is a sectional view along the line A-A' of the fuse device shown in FIG. 1(a).

FIG. 2(a) is a plan view showing a fuse device of a second embodiment. FIG. 2(b) is a side view of the fuse device shown in FIG. 2(a) from a lower side of FIG. 2(a).

FIG. 2(c) is a side view of the fuse device shown in FIG. 2(a) from a right side of FIG. 2(a).

FIG. 3(a) is a plan view of a fuse device of a third embodiment. FIG. 3(b) is a side view of the fuse device shown in FIG. 3(a) from a lower side of FIG. 3(a). FIG. 3(c) is a side view of the fuse device shown in FIG. 3(a) from a right side of FIG. 3(a). FIG. 3(d) is a perspective view showing a fuse element provided in the fuse device shown in FIG. 3(a).

FIG. 4(a) is a plan view showing a fuse device of a fourth embodiment. FIG. 4(b) is a side view of the fuse device shown in FIG. 4(a) from a lower side of FIG. 4(a).

FIG. 4(c) is a side view of the fuse device shown in FIG. 4(a) from a right side of FIG. 4(a).

FIG. 5(a) is a plan view showing a protection device of a fifth embodiment.

FIG. 5(b) is a sectional view along the line B-B' of the protection device shown in FIG. 5(a). FIG. 5(c) is a side view of the protection device shown in FIG. 5(a) from a right side of FIG. 5(a).

FIG. 6(a) is a plan view showing a protection device of a sixth embodiment. FIG. 6(b) is a side view of the protection device shown in FIG. 6(a) from a lower side of FIG. 6(a). FIG. 6(c) is a side view of the protection device shown in FIG. 6(a) from a right side of FIG. 6(a).

DESCRIPTION OF EMBODIMENTS

Hereinafter, a fuse element, a fuse device, and a protection device according to the invention will be described in detail 40 appropriately referring to the drawings. The drawings used in the following descriptions may be drawn with feature portions enlarged for convenience to facilitate understanding of the features of the invention, and dimensional ratios and the like between the constituent elements may differ from the actual values. Materials, dimensions, and the like exemplified in the following description are merely examples, which are not intended to limit the invention, and can be appropriately changed within a range in which effects of the invention are obtained.

First Embodiment (Fuse Device)

FIG. 1(a) is a plan view showing a fuse device of a first embodiment, and FIG. 1(b) is a sectional view along the line 55 A-A' of the fuse device shown in FIG. 1(a). As shown in FIG. 1(a), a fuse device 10 of the embodiment has a first terminal 20a, a second terminal 20b, and a fuse element 1 of the embodiment composed of a blowout section 1e disposed between the first terminal 20a and the second terminal 20b. (Fuse Element)

The fuse element 1 provided in the fuse device 10 of the embodiment is composed of the blowout section 1e. The fuse element 1 electrically connects the first terminal 20a and the second terminal 20b. The blowout section 1e (fuse element 1) is joined to the first terminal 20a and the second terminal 20b by a conductive connection member, such as solder, to be electrically connected.

As shown in FIG. 1(a), the blowout section 1e is a flat plate-shaped section with no through-hole, and the thickness of which is substantially constant. As shown in FIG. 1(a), the blowout section 1e has a substantially rectangular shape in a plan view having a direction connecting the first terminal 20a and the second terminal 20b as a long side and a direction substantially perpendicular to the direction connecting the first terminal 20a and the second terminal 20b (hereinafter, also referred to as a "width direction") as a short side.

In the fuse device 10 shown in FIG. 1(a), although a case where the blowout section 1e includes the fuse element 1 having a substantially rectangular shape in a plan view has been described as an example, the shape of the blowout section of the fuse element is not limited to the substantially rectangular shape in a plan view. For example, a width and a thickness of the blowout section 1e may not be constant.

A blowout temperature of the blowout section 1e is preferably 140° C. to 400° C. In a case where the blowout temperature of the blowout section 1e is equal to or higher than 140° C., preferably, the fuse device 10 is not blown out at a normally used temperature. In a case where the blowout temperature of the blowout section 1e is equal to or lower than 400° C., the first terminal 20a and the second terminal 20b can be prevented from reaching a high temperature at the time of blowout and negatively affecting members connected to the first terminal 20a and the second terminal 20b.

In the fuse device 10 of the embodiment, as shown in FIG. 1(b), the blowout section 1e (fuse element 1) is preferably formed of a flat plate-shaped low-melting-point metal layer 1a having a rectangular shape in sectional view and a high melting metal layer 1b laminated in such a manner that the entire surface of the low-melting-point metal layer 1a is coated at a substantially constant thickness. In this case, as shown in FIG. 1(b), the blowout section 1e has a three-layered structure composed of the low-melting-point metal layer 1a and high-melting-point metal layers 1b laminated on both surfaces of the low-melting-point metal layer 1a in a thickness direction, and all side surfaces of the low-melting-point metal layer 1a are coated with the high-melting-point metal layers 1b. For this reason, leakage of the low-melting-point metal layer 1a from the blowout section 1e or inflow of the conductive connection member, such as solder, into the blowout section 1e due to heating at the time of reflow in a manufacturing process of the fuse device 10 is suppressed. As a result, fluctuation of a resistance value of the blowout section 1e due to deformation of the blowout section 1e (fuse element 1) at the time of the reflow in the manufacturing process of the fuse device 10 is suppressed, and the fuse device 10 having a stable blowout characteristic can be easily manufactured.

The low-melting-point metal layer 1a is preferably composed of Sn or an alloy containing Sn as a primary constituent. The content of Sn in the alloy containing Sn as a primary constituent is preferably equal to or greater than 50 mass %, and more preferably, equal to or greater than 60% by mass. Examples of the alloy containing Sn as a primary constituent include a Sn—Bi alloy, an In—Sn alloy, and a Sn—Ag—Cu alloy.

The high-melting-point metal layer 1b is preferably a layer having a higher melting point than the low-melting-point metal layer 1a and is a layer composed of a metal material that is dissolved by a molten material of the low-melting-point metal layer 1b.

The melting point of the high-melting-point metal layer 1b is preferably within a range of a temperature at least 100°

C. higher than the melting point of the low-melting-point metal layer 1a and equal to or lower than a temperature 900° C. higher than the melting point of the low-melting-point metal layer 1a.

5 The high-melting-point metal layer 1b is preferably composed of any one selected from Ag, Cu, an alloy containing Ag as a primary constituent, and an alloy containing Cu as a primary constituent, and more preferably, composed of Ag or an alloy containing Ag as a primary constituent. The 10 content of Ag in the alloy containing Ag as a primary constituent is preferably equal to or greater than 50% by mass, and more preferably, equal to or greater than 60% by mass. Examples of the alloy containing Ag as a primary constituent include a silver-palladium alloy. Ag is a noble 15 metal, has a low ionization tendency, is not easily oxidized in the atmosphere, and is easily dissolved by the molten material of the low-melting-point metal layer 1a. For this reason, Ag or the alloy containing Ag as a primary constituent is suitably used as the material of the high-melting-point metal layer 1b.

20 The blowout section 1e (fuse element 1) can be made, for example, in such a manner that the low-melting-point metal layer 1a is composed of an alloy containing Sn as a primary constituent, the high-melting-point metal layer 1b is composed of Ag, and a ratio of the thickness of the low-melting-point metal layer 1a to the total thickness of the high-melting-point metal layers 1b (low-melting-point metal layer 1a:high-melting-point metal layers 1b) is 1:1 to 50:1. The blowout section 1e has the blowout temperature of 140° 25 C. to 400° C.

25 The blowout section 1e (fuse element 1) has volume resistivity (specific resistance) of about $7.4 \mu\Omega\cdot\text{cm}$ in a case where the low-melting-point metal layer 1a is composed of the alloy containing Sn as a primary constituent, the high-melting-point metal layer 1b is composed of Ag, and the ratio (low-melting-point metal layer 1a:high-melting-point metal layer 1b) of the thickness of the low-melting-point metal layer 1a to the total thickness of the high-melting-point metal layers 1b is 10:1.

30 The fuse element 1 can be manufactured, for example, using a plating method. Specifically, a metal foil having a shape corresponding to the low-melting-point metal layer 1a of the fuse element 1 is prepared, and the high-melting-point metal layer 1b is formed on the entire surface of the metal 35 foil using a plating method. With this, the flat plate-shaped fuse element 1 in which the entire surface of the low-melting-point metal layer 1a is coated with the high-melting-point metal layer 1b having a substantially constant thickness is obtained.

40 (First Terminal, Second Terminal)

45 In using the fuse device 10, the first terminal 20a and the second terminal 20b are joined to terminal sections of an electric circuit (not shown) to be electrically connected to the electric circuit. As shown in FIG. 1(a), an attachment 50 hole 3a composed of a circular through-hole is provided in a center portion of the first terminal 20a. Similarly to the first terminal 20a, an attachment hole 3b composed of a circular through-hole is provided in a center portion of the second terminal 20b. The fuse device 10 of the embodiment is 55 attachably and detachably attached at a predetermined position using joining members, such as bolts, and the attachment holes 3a and 3b.

60 As shown in FIG. 1(a), widths 2d of joining portions joining the first terminal 20a and the second terminal 20b to the blowout section 1e are identical. Planar shapes of the first terminal 20a and the second terminal 20b are substantially symmetric with the blowout section 1e sandwiched

therebetween and are substantially symmetric with respect to a center of the blowout section $1e$ in a width $1d$ direction.

The planar shapes of the first terminal $20a$ and the second terminal $20b$ are not limited to the example shown in FIG. 1(a). For example, planar shapes of the attachment holes $3a$ and $3b$ are not limited to circular shapes, and may be elliptical shapes, polygonal shapes, and the like. Instead of the attachment holes $3a$ and $3b$, notches may be provided such that the first terminal $20a$ and the second terminal $20b$ have a C-shape in a plan view. In a case where the widths $2d$ of the joining portions joining the first terminal $20a$ and the second terminal $20b$ to the blowout section $1e$ are identical, the planar shapes of the first terminal $20a$ and the second terminal $20b$ may not be substantially symmetric with the blowout section $1e$ sandwiched therebetween or may not be substantially symmetric with respect to the center of the blowout section $1e$ in the width $1d$ direction.

The first terminal $20a$ and the second terminal $20b$ are formed of a material having conductivity. For example, the first terminal $20a$ and the second terminal $20b$ can be composed of Cu or an alloy containing Cu as a primary constituent. Examples of the alloy containing Cu as a primary constituent include a Cu—Ni alloy.

In the fuse device 10 of the embodiment, as shown in FIG. 1(a), the width $1d$ of the blowout section $1e$ in a plan view has a length ($\{1d/2d\} \times 100 \geq 80\%$) equal to or greater than 80% of the width $2d$ of each of the joining portions joining the first terminal $20a$ and the second terminal $20b$ to the blowout section $1e$, is preferably a length equal to or greater than 95% of the width $2d$ of each of the joining portions, and more preferably exceeds 100% of the width $2d$ of each of the joining portions.

In the specification, the width $1d$ of the blowout section $1e$ in a case where the length of the blowout section in the width direction is not constant is a length of a portion having a shortest length in the width direction. The width $2d$ of each of the joining portions joining the first terminal $20a$ and the second terminal $20b$ to the blowout section $1e$ is a length parallel to the width $1d$ of the blowout section $1e$ in each of portions of the first terminal $20a$ and the second terminal $20b$ closest to the blowout section $1e$.

In a case where the width $1d$ of the blowout section $1e$ is the length equal to or greater than 80% described above, an effect of decreasing the resistance of the blowout section $1e$ due to the large the width $1d$ of the blowout section $1e$ is sufficiently obtained. The width $1d$ of the blowout section $1e$ is preferably equal to or less than 200% of the width $2d$ of each of the joining portions joining the first terminal $20a$ and the second terminal $20b$ to the blowout section $1e$, and more preferably, equal to or less than 150%. In a case where the width $1d$ of the blowout section $1e$ is the length equal to or less than 200% described above, an influence on a reduction in size of the fuse device 10 can be suppressed due to the excessive width $1d$ of the blowout section $1e$.

The fuse device 10 shown in FIGS. 1(a) and 1(b) can be manufactured by a known method. For example, the fuse device 10 can be manufactured by a method in which the fuse element 1 (blowout section $1e$) is joined to the first terminal $20a$ and the second terminal $20b$ by a conductive connection member, such as solder, to be electrically connected.

The blowout section $1e$ of the fuse device 10 of the embodiment is not blown out while a rated current flows through an electric circuit joined thereto through the first terminal $20a$ and the second terminal $20b$. In a case where an overcurrent exceeding the rated current flows through the above-described electric circuit, the blowout section $1e$ is

blown out, the first terminal $20a$ and the second terminal $20b$ are disconnected, and a current path of the electric circuit is cut off.

In a case where the blowout section $1e$ is formed in such a manner that the low-melting-point metal layer $1a$ and the high-melting-point metal layer $1b$ are laminated in the thickness direction, and in a case where an overcurrent exceeding the rated current flows through the electric circuit, the low-melting-point metal layer $1a$ of the blowout section $1e$ generates heat and is melted, the high-melting-point metal layer $1b$ is dissolved by a generated molten material of the low-melting-point metal layer $1a$, and the blowout section 1 is quickly blown out.

The fuse device 10 of the embodiment in which the width $1d$ of the blowout section $1e$ is the length equal to or greater than 80% of the width $2d$ of each of the joining portions joining the first terminal $20a$ and the second terminal $20b$ to the blowout section $1e$ has the blowout section $1e$ that has the large width $1d$ and low resistance, and can thus contribute to an increase in rated current.

In a case where the blowout temperature of the blowout section $1e$ in the fuse device 10 of the embodiment is equal to or lower than 400°C ., the first terminal $20a$ and the second terminal $20b$ can be prevented from reaching a high temperature at the time of blowout and adversely influencing a member connected to the first terminal $20a$ and the second terminal $20b$, and an electronic apparatus to which the fuse device 10 is attached can be restrained from exceeding a heat resistance temperature. Accordingly, in a case where the blowout temperature of the blowout section $1e$ is equal to or lower than 400°C ., there is no need to provide a plurality of small holes in the blowout section or to thin the width of the blowout section to form a local heat-generating point such that the first terminal $20a$ and the second terminal $20b$ are not excessively heated.

In a case where the blowout temperature of the blowout section $1e$ is equal to or lower than 400°C ., there is no need to form a heat-generating point in the blowout section $1e$ and increase the length of the blowout section $1e$ to increase a distance between the heat-generating point and each of the first terminal $20a$ and the second terminal $20b$ such that the first terminal $20a$ and the second terminal $20b$ are not excessively heated. Accordingly, in a case where the blowout temperature of the blowout section $1e$ is equal to or lower than 400°C ., the length of the blowout section $1e$ (the distance between the first terminal $20a$ and the second terminal $20b$) can be reduced, compared to a case where the blowout temperature of the blowout section $1e$ exceeds 400°C .

The length and the resistance value of the blowout section $1e$ (fuse element 1) have a proportional relationship. Accordingly, as the length of the fuse element 1 is reduced, the resistance value of the fuse element 1 decreases. As described above, in a case where the blowout temperature of the blowout section $1e$ is equal to or lower than 400°C ., it is possible to reduce the length of the blowout section $1e$, compared to a case where the blowout temperature of the blowout section $1e$ exceeds 400°C . Thus, it is possible to make the blowout section $1e$ that is small in size and has lower resistance. As a result, the size of the fuse device 10 can be reduced and the rated current can be further increased.

In a case where the blowout temperature of the blowout section $1e$ is equal to or lower than 400°C ., the length of the blowout section $1e$ can be reduced. For this reason, the resistance value of the blowout section $1e$ can be decreased and the rated current can be increased even though the

blowout section 1e is formed of a material having high volume resistivity, for example, compared to a fuse element (volume resistivity 1.62 $\mu\Omega\cdot\text{cm}$) that is composed of copper since the melting point (1085°C) is high and the blowout temperature of the blowout section exceeds 400°C.

Second Embodiment (Fuse Device)

FIG. 2(a) is a plan view showing a fuse device of a second embodiment. FIG. 2(b) is a side view of the fuse device shown in FIG. 2(a) from a lower side of FIG. 2(a). FIG. 2(c) is a side view of the fuse device shown in FIG. 2(a) from a right side of FIG. 2(a). FIGS. 2(a) and 2(c) show a state in which a cover member 5 of a fuse device 20 shown in FIG. 2(b) is removed.

As shown in FIGS. 2(a) to 2(c), the fuse device 20 includes a fuse element 11, an insulating substrate 4, and a first electrode 2a and a second electrode 2b disposed on a front surface 4a of the insulating substrate 4. Each of the first electrode 2a and the second electrode 2b functions as a terminal that is conductively connected to the fuse element 11.

A difference between the fuse element 11 provided in the fuse device 20 of the second embodiment shown in FIGS. 2(a) to 2(c) and the fuse element 1 provided in the first embodiment is only that, in the fuse element 11 shown in FIGS. 2(a) to 2(c), side surfaces in a direction connecting the first electrode 2a and the second electrode 2b are not coated with the high-melting-point metal layer 1b, and the low-melting-point metal layer 1a is exposed on the side surfaces. Accordingly, the fuse element 11 provided in the fuse device 20 of the second embodiment has the same materials and layer structure as the fuse element 1 provided in the first embodiment. For this reason, the fuse element 11 provided in the second embodiment will be described focusing on only a difference from the fuse element 1 provided in the first embodiment.

In the fuse device 20 of the embodiment, as shown in FIGS. 2(a) and 2(b), the fuse element 11 has a blowout section 11e disposed between the first electrode 2a and the second electrode 2b, a first joint portion 11f joined onto the first electrode 2a by a conductive connection member (not shown), such as solder, and a second joint portion 11g joined onto the second electrode 2b by a conductive connection member (not shown), such as solder. As shown in FIG. 2(b), a space is formed between the blowout section 11e and the front surface 4a of the insulating substrate 4.

In the fuse element 11 provided in the fuse device 20 of the second embodiment, as shown in FIG. 2(b), a side surface that is joined to the first electrode 2a or the second electrode 2b is coated with the high-melting-point metal layer 1b. For this reason, leakage of the low-melting-point metal layer 1a from the blowout section 11e or inflow of the conductive connection member, such as solder, into the blowout section 11e due to heating at the time of reflow in a manufacturing process of the fuse device 20 is suppressed. As a result, fluctuation of the resistance value of the blowout section 11e due to deformation of the blowout section 11e (fuse element 11) at the time of the reflow in the manufacturing process of the fuse device 20 is suppressed, and the fuse device 20 having stable blowout characteristics can be easily manufactured.

The fuse element 11 can be manufactured, for example, using an electroless plating method. Specifically, a band-shaped (ribbon-shaped) metal foil that will become the low-melting-point metal layer 1a is prepared. As the metal foil, a metal foil having a width corresponding to the length

of the low-melting-point metal layer 1a of the fuse element 11 in the direction connecting the first electrode 2a and the second electrode 2b is used. Next, the high-melting-point metal layer 1b is formed on the surface of the metal foil 5 using an electroless plating method, and a band-shaped laminate is obtained. Thereafter, the length of the band-shaped laminate is cut at a predetermined dimension to be made into a flat plate shape. With this, the fuse element 11 that has a predetermined rectangular shape and in which the 10 low-melting-point metal layer 1a is exposed on cut sections is obtained. This manufacturing method is particularly suitable for a case of manufacturing a small-sized fuse element.

Even in the fuse device 20 of the embodiment, as in the first embodiment, as shown in FIG. 2(c), a width 1d of the 15 blowout section 11e in the plan view has a length ($\{1d/2d\} \times 100 \geq 80\%$)) equal to or greater than 80% of a width 2d of each of joining portions joining the first electrode 2a and the second electrode 2b to the blowout section 11e, is preferably a length equal to or greater than 95% of the width 2d of each 20 of the joining portions, and is more preferably a length exceeding 100% of the width 2d of each of the joining portions.

In the fuse element 11 provided in the fuse device 20 of the embodiment, the low-melting-point metal layer 1a is exposed on the side surfaces in the direction connecting the first electrode 2a and the second electrode 2b. That is, the low-melting-point metal layer 1a is exposed on the surfaces of the fuse element 11 in a direction substantially perpendicular to the direction connecting the first electrode 2a and the second electrode 2b. For this reason, the width 1d of the blowout section 11e in a plan view is more preferably a length exceeding 100% of the width 2d of the joining portion joining the first electrode 2a or the second electrode 2b to the blowout section 11e (the width 1d is greater than the width 2d) for the following reason. It is possible to more effectively suppress the contact of the conductive connection member, such as solder, and the low-melting-point metal layer 1a of the fuse element 11 at the time of the reflow in the manufacturing process of the fuse device 20 with the high-melting-point metal layer 1b with which the side surfaces of the fuse element 11 joined to the first electrode 2a and the second electrode 2b are coated. As a result, fluctuation of the resistance value of the blowout section 11e due to deformation of the blowout section 11e (fuse element 11) at the time of the reflow is suppressed, and the fuse device 20 having stable blowout characteristics can be easily manufactured.

The insulating substrate 4 is not particularly limited as long as the insulating substrate has electrical insulation, and, for example, a known insulating substrate that is used as a circuit board, such as a resin substrate, a ceramic substrate, or a composite substrate of a resin and a ceramic can be used. Specific examples of the resin substrate include an epoxy resin substrate, a phenol resin substrate, and a polyimide substrate. Specific examples of the ceramic substrate include an alumina substrate, a glass ceramic substrate, a mullite substrate, and a zirconia substrate. Specific examples of the composite substrate include a glass epoxy substrate.

The first electrode 2a and the second electrode 2b are 60 disposed at a pair of facing end portions of the insulating substrate 4. Each of the first electrode 2a and the second electrode 2b is formed of a conductive pattern, such as Ag wiring or Cu wiring.

Each of the surfaces of the first electrode 2a and the second electrode 2b may be coated with an electrode protection layer to suppress changes in electrode characteristics due to oxidation or the like. As a material of the electrode

11

protection layer, a Sn-plated film, a Ni/Au-plated film, a Ni/Pd-plated film, a Ni/Pd/Au-plated film, or the like can be used.

The first electrode **2a** and the second electrode **2b** are electrically connected to a first external connection electrode **42a** and a second external connection electrode **42b** formed on a rear surface **4b** of the insulating substrate **4** through castellations **21a** and **21b**, respectively. The connection of the first electrode **2a** and the first external connection electrode **42a** and the connection of the second electrode **2b** and the second external connection electrode **42b** may be performed through through-holes.

In the fuse device **20** of the embodiment, as shown in FIG. 2(b), the cover member **5** is preferably attached through an adhesive. With the attachment of the cover member **5**, the inside of the fuse device **20** is protected, and scattering of a molten material generated in a case where the fuse element **11** is blown out can be prevented. As a material of the cover member **5**, various engineering plastics and/or ceramics can be used.

The fuse device **20** of the embodiment is mounted on a current path of the circuit board (not shown) through the first external connection electrode **42a** and the second external connection electrode **42b** for use. While a rated current is flowing to the current path of the circuit board, the blowout section **11e** of the fuse element **11** provided in the fuse device **20** is not blown out. In a case where an overcurrent exceeding the rated current flows through the current path of the circuit board, the blowout section **11e** is blown out, whereby the first electrode **2a** and the second electrode **2b** are disconnected and the current path of the circuit board is cut off.

In a case where the blowout section **11e** is formed in such a manner that the low-melting-point metal layer **1a** and the high-melting-point metal layer **1b** are laminated in the thickness direction, and in a case where the overcurrent exceeding the rated current flows through the current path of the circuit board, the low-melting-point metal layer **1a** of the blowout section **11e** generates heat to be melted, the high-melting-point metal layer **1b** is dissolved by a generated molten material of the low-melting-point metal layer **1a**, and the blowout section **11e** is quickly blown out.

Similarly to the fuse device **10** of the first embodiment, the fuse device **20** of the embodiment in which the width **1d** of the blowout section **11e** is the length equal to or greater than 80% of the width **2d** of each of the joining portions joining the first electrode **2a** and the second electrode **2b** to the blowout section **11e** has the blowout section **11e** that has the large width **1d** and low resistance, and can thus contribute to an increase in rated current.

In a case where the blowout temperature of the blowout section **11e** in the fuse device **20** of the embodiment is equal to or lower than 400°C., first electrode **2a** and the second electrode **2b** can be restrained from reaching a high temperature at the time of blowout and adversely influencing a member connected to the first electrode **2a** and the second electrode **2b**, and the circuit board to which the first external connection electrode **42a** and the second external connection electrode **42b** are connected. Accordingly, the length of the blowout section **11e** (the distance between the first electrode **2a** and the second electrode **2b**) can be reduced, the size of the fuse device **20** can be reduced, and the rated current can be further increased, compared to a case where the blowout temperature of the blowout section **11e** exceeds 400°C.

Third Embodiment (Fuse Device)

FIG. 3(a) is a plan view showing a fuse device of a third embodiment. FIG. 3(b) is a side view of the fuse device

12

shown in FIG. 3(a) from a lower side of FIG. 3(a). FIG. 3(c) is a side view of the fuse device shown in FIG. 3(a) from a right side of FIG. 3(a). FIGS. 3(a) and 3(c) show a state in which a cover member **5** of a fuse device **25** shown in FIG. 3(b) is removed. FIG. 3(d) is a perspective view showing a fuse element provided in the fuse device shown in FIG. 3(a).

As shown in FIGS. 3(a) to 3(c), the fuse device **25** includes a fuse element **15** shown in FIG. 3(d), an insulating substrate **4**, and a first electrode **2a** and a second electrode **2b** disposed on a front surface **4a** of the insulating substrate **4**. As in the second embodiment, each of the first electrode **2a** and the second electrode **2b** functions as a terminal that is conductively connected to the fuse element **15**.

A difference between the fuse device **25** of the third embodiment shown in FIGS. 3(a) to 3(c) and the fuse device **20** shown in the second embodiment is only a thickness (shape) of high-melting-point metal layer **1b** in a first joint portion **15f** and a second joint portion **15g** of the fuse element **15** provided in the fuse device **25** shown in FIG. 3(a) to FIG. 3(c). Accordingly, in the third embodiment, description will be provided focusing on only a difference from the second embodiment, and the same members as those in the second embodiment are represented by the same reference numerals and description thereof will not be repeated.

In the fuse element **15** provided in the fuse device **25** of the third embodiment, as shown in FIGS. 3(b) and 3(d), the thickness of the high-melting-point metal layer **1b** in the first joint portion **15f** and the second joint portion **15g** is greater than that in the blowout section **15e**. This gives a cut section of the fuse element **15** shown in FIGS. 3(b) and 3(d) a dog-bone shape. The first joint portion **15f** is a portion that is joined to the first electrode **2a** by a conductive connection member (not shown), such as solder. The second joint portion **15g** is a portion that is joined to the second electrode **2b** by a conductive connection member (not shown), such as solder. For this reason, in the fuse device **25** of the third embodiment, it is possible to effectively suppress the contact of the conductive connection member, such as solder, and the low-melting-point metal layer **1a** of the fuse element **15** at the time of reflow in a manufacturing process of the fuse device **25**, with the high-melting-point metal layer **1b** that forms the first joint portion **15f** and the second joint portion **15g**. As a result, fluctuation of a resistance value of the blowout section **15e** due to deformation of the blowout section **15e** (fuse element **15**) at the time of the reflow is more effectively suppressed, and the fuse device **25** having stable blowout characteristics can be easily manufactured. As shown in FIG. 3(c), the width **1d** of the blowout section **15e** in a plan view has a length greater than 100% and equal to or less than 200% of the width **2d** of each of the joining portions joining the first electrode **2a** and the second electrode **2b** to the blowout section **15e**. With this width relationship, when the fuse element **15** is joined to the first electrode **2a** and the second electrode **2b** by a conductive connection member such as solder, contact between the solder and the low-melting-point metal layer **1a** does not occur. As shown in FIGS. 3(b) and 3(d), the thickness of the high-melting-point metal layer **1b** in the first joint portion **15f** and the second joint portion **15g** is greater than that in the blowout section **15e**, which further prevents contact between the solder and the low-melting-point metal layer **1a**. As shown in FIG. 3(d), the low-melting-point metal layer **1a** is exposed on the side surfaces in the direction connecting the first electrode **2a** and the second electrode **2b**. This configuration effectively prevents leakage of the low-melting-point metal layer **1a** from the blowout section **15e** and

inflow of the conductive connection member into the blowout section **15e** during reflow in the manufacturing process.

The fuse element **15** can be manufactured, for example, using an electroplating method. Specifically, a band-shaped (ribbon-shaped) metal foil that will become the low-melting-point metal layer **1a** is prepared. As the metal foil, a metal foil having a width corresponding to a length of the low-melting-point metal layer **1a** of the fuse element **15** in a direction connecting the first electrode **2a** and the second electrode **2b** is used. Next, the high-melting-point metal layer **1b** is formed on the surface of the metal foil using the electroplating method, and a band-shaped laminate is obtained. Thereafter, the length of the band-shaped laminate is cut at a predetermined dimension to be made into a flat plate shape. With this, the fuse element **15** that has a predetermined rectangular shape and in which the low-melting-point metal layer **1a** is exposed on the cut sections is obtained.

In the embodiment, the high-melting-point metal layer **1b** is formed to be thicker in end portions in a width direction than in a center portion in the width direction of the band-shaped metal foil due to current concentration at the time of electroplating processing. For this reason, as shown in FIG. 3(d), the fuse element **15** has a cut section in a dog-bone shape in which the thickness of the high-melting-point metal layer **1b** of each of the first joint portion **15f** and the second joint portion **15g** is greater than that in the blowout section **15e**. This manufacturing method is particularly suitable for a case of manufacturing a small-sized fuse element.

In the fuse device **25** of the embodiment, as in the first embodiment and the second embodiment, as shown in FIG. 3(c), a width **1d** of the blowout section **15e** in a plan view is preferably a length ($\{1d/2d\} \times 100 \geq 80\%$) equal to or greater than 80% of a width **2d** of each of joining portions joining the first electrode **2a** and the second electrode **2b** to the blowout section **15e**, is preferably a length equal to or greater than 95% of the width **2d** of each of the joining portions, and more preferably exceeds 100% of the width **2d** of each of the joining portions.

In the fuse element **15** provided in the fuse device **25** of the embodiment, the low-melting-point metal layer **1a** is exposed on the side surfaces in the direction connecting the first electrode **2a** and the second electrode **2b**. For this reason, as in the second embodiment, the width **1d** of the blowout section **15e** in a plan view is more preferably a length exceeding 100% of the width **2d** of each of the joining portions joining the first electrode **2a** and the second electrode **2b** to the blowout section **15e**.

Similarly to the fuse devices of the first embodiment and the second embodiment, the fuse device **25** of the embodiment in which the width **1d** of the blowout section **15e** is the length equal to or greater than 80% of the width **2d** of each of the joining portions joining the first electrode **2a** and the second electrode **2b** to the blowout section **15e** has the blowout section **15e** that has the large width **1d** and low resistance, and can thus contribute to an increase in rated current.

In a case where a blowout temperature of the blowout section **11e** in the fuse device **25** of the embodiment is equal to or lower than 400°C ., the first electrode **2a** and the second electrode **2b** can be prevented from reaching a high temperature at the time of blowout and adversely influencing a member connected to the first electrode **2a** and the second electrode **2b**, and the circuit board to which the first external connection electrode **42a** and the second external connection electrode **42b** are connected. Accordingly, the length of the

blowout section **11e** (the distance between the first electrode **2a** and the second electrode **2b**) can be reduced, the size of the fuse device **25** can be reduced, and the rated current can be increased, compared to a case where the blowout temperature of the blowout section **11e** exceeds 400°C .

Fourth Embodiment (Fuse Device)

FIG. 4(a) is a plan view showing a fuse device of a fourth embodiment. FIG. 4(b) is a side view of the fuse device shown in FIG. 4(a) from a lower side of FIG. 4(a). FIG. 4(c) is a side view of the fuse device shown in FIG. 4(a) from a right side of FIG. 4(a). FIGS. 4(a) and 4(c) show a state in which a cover member **5** of a fuse device **40** shown in FIG. 4(b) is removed.

As shown in FIGS. 4(a) to 4(c), the fuse device **40** includes a fuse element **50**, an insulating substrate **4**, and a first electrode **2a** and a second electrode **2b** disposed on a front surface **4a** of the insulating substrate **4**.

In the fourth embodiment, as the fuse element **50**, the same fuse element as the fuse element **11** provided in the second embodiment is provided. In other words, the configuration of a cross section of the fuse element **50** perpendicular to an in-plane direction of the insulating substrate **4** of the fuse device **40** shown in FIG. 4(a) is the same as the configuration of a cross section of the fuse element **20** perpendicular to an in-plane direction of the insulating substrate **4** of the fuse device **20** shown in FIG. 2(a). For this reason, in the fourth embodiment, description of the blowout temperature, the materials, and the layer structure of the fuse element **50** will not be repeated.

As shown in FIGS. 4(a) and 4(b), the fuse element **50** provided in the fuse device **40** of the embodiment has a blowout section **51** disposed between the first electrode **2a** and the second electrode **2b**, a first joint portion **52a** joined onto the first electrode **2a** by a conductive connection member (not shown), such as solder, and a second joint portion **52b** joined onto the second electrode **2b** by a conductive connection member (not shown), such as solder. As shown in FIG. 4(b), a space is formed between the blowout section **51** and the front surface **4a** of the insulating substrate **4**.

In the embodiment, as shown in FIG. 4(b), the fuse element **50** is continuously covered from the top of the first electrode **2a** and the second electrode **2b** over the side surfaces of the insulating substrate **4**. With this, the first electrode **2a** and the second electrode **2b** are electrically connected to a first external connection electrode **42a** and a second external connection electrode **42b** disposed on a rear surface **4b** of the insulating substrate **4** through the fuse element **50**.

In the embodiment, the first joint portion **52a** is electrically connected to the first external connection electrode **42a**, and functions as a terminal that is conductively connected to the blowout section **51** of the fuse element **50**. The second joint portion **52b** is electrically connected to the second external connection electrode **42b**, and functions as a terminal that is conductively connected to the blowout section **51** of the fuse element **50**.

In the fuse device **40** of the embodiment, since the first joint portion **52a** and the second joint portion **52b** composed of a part of the band-shaped fuse element **50** function as terminals, a width of the blowout section **51** in a plan view is identical to a width of each of the first joint portion **52a** and the second joint portion **52b**. Therefore, the width of the blowout section **51** in a plan view has a length of 100% of

15

a width of each of joining portions joining the first joint portion **52a** and the second joint portion **52b** to the blowout section **51**.

In the fuse device **40** of the embodiment, the insulating substrate **4**, the first electrode **2a**, the second electrode **2b**, the first external connection electrode **42a**, and the second external connection electrode **42b** that are the same as those in the fuse device **20** of the second embodiment can be used.

Similarly to the fuse device **20** of the second embodiment, as shown in FIG. 4(b), the cover member **5** is preferably attached to the fuse device **40** of the embodiment through an adhesive. As a material of the cover member **5**, the same material as in the fuse device **20** of the second embodiment can be used.

The fuse device **40** of the embodiment is mounted on a current path of a circuit board (not shown) through the first external connection electrode **42a** and the second external connection electrode **42b** for use. In a case where an overcurrent exceeding a rated current flows through the current path of the circuit board, the blowout section **51** is blown out, whereby the first electrode **2a** and the second electrode **2b** are disconnected and the current path of the circuit board is cut off.

In a case where the blowout section **51** is formed in such a manner that a low-melting-point metal layer **1a** and high-melting-point metal layer **1b** are laminated in a thickness direction, and in a case where the overcurrent exceeding the rated current flows through the current path of the circuit board, the low-melting-point metal layer **1a** of the blowout section **51** generates heat and is melted, the high-melting-point metal layer **1b** is dissolved by a generated molten material of the low-melting-point metal layer **1a**, and the blowout section **51** is quickly blown out.

The fuse device **40** of the embodiment in which the width of the blowout section **51** is the length of 100% of the width of each of the joining portions joining the first joint portion **52a** and the second joint portion **52b** to the blowout section **51** has the blowout section **51** that has a large width and low resistance, and can thus contribute to an increase in rated current.

In a case where a blowout temperature of the blowout section **51** in the fuse device **40** of the embodiment is equal to or lower than 400°C., the first electrode **2a** and the second electrode **2b** can be restrained from reaching a high temperature at the time of blowout and adversely influencing a member connected to the first electrode **2a** and the second electrode **2b**, and the circuit board to which the first external connection electrode **42a** and the second external connection electrode **42b** are connected. Accordingly, the length of the blowout section **51** (the distance between the first joint portion **52a** and the second joint portion **52b**) can be reduced, the size of the fuse device **40** can be reduced, and the rated current can be further increased, compared to a case where the blowout temperature of the blowout section **51** exceeds 400°C.

Fifth Embodiment (Protection Device)

FIG. 5(a) is a plan view of a protection device of a fifth embodiment. FIG. 5(b) is a sectional view along the line B-B' of the protection device shown in FIG. 5(a). FIG. 5(c) is a side view of the protection device shown in FIG. 5(a) from a right side of FIG. 5(a). FIGS. 5(a) and 5(c) show a state in which a cover member **5** of a protection device **30** shown in FIG. 5(b) is removed.

As shown in FIGS. 5(a) to 5(c), the protection device **30** includes a fuse element **11**, a heat-generating element **7** that

16

heats the fuse element **11** to be blown out, an insulating substrate **4**, and a first electrode **2a** and a second electrode **2b** disposed on a front surface **4a** of the insulating substrate **4**. In the protection device **30** of the embodiment, as shown in FIG. 5(b), the fuse element **11** is disposed across the first electrode **2a** and the second electrode **2b**. That is, the fuse element **11** spans from the first electrode **2a** to the second electrode **2b**. Each of the first electrode **2a** and the second electrode **2b** functions as a terminal that is conductively connected to the fuse element **11**. The protection device **30** of the embodiment has a first heat-generating element electrode **9a** and a second heat-generating element electrode **9b** that are connected to the heat-generating element **7**, and a heat-generating element lead-out electrode **9** that is connected to the second heat-generating element electrode **9b**.

The protection device **30** of the fifth embodiment includes, as the fuse element **11**, the insulating substrate **4**, the first electrode **2a**, and the second electrode **2b**, the same ones provided in the fuse device **20** of the second embodiment. For this reason, in the fifth embodiment, description of the blowout temperature, the materials, and the layer structure of the fuse element **11** will not be repeated. In the fifth embodiment, description of the insulating substrate **4**, the first electrode **2a**, and the second electrode **2b** will not be repeated.

In the protection device **30** of the embodiment, as shown in FIGS. 5(a) and 5(b), the fuse element **11** has a blowout section **11e** disposed between the first electrode **2a** and the second electrode **2b**, a first joint portion **11** joined onto the first electrode **2a** by a conductive connection member (not shown), such as solder, and a second joint portion **11g** joined onto the second electrode **2b** by a conductive connection member (not shown), such as solder.

In the protection device **30** of the embodiment, as shown in FIG. 5(b), a surface of the blowout section **11e** on the insulating substrate **4** side and the heat-generating element lead-out electrode **9** are electrically connected. The blowout section **11e** and the heat-generating element lead-out electrode **9** are electrically connected by a conductive connection member (not shown), such as solder.

In the protection device **30** of the embodiment, as shown in FIG. 5(b), the blowout section **11e** is in a protruding shape on an opposite side to the front surface **4a** of the insulating substrate **4** in sectional view. Further, the heat-generating element **7** disposed on the front surface **4a** of the insulating substrate **4**, an insulating member **8** with which the heat-generating element **7** is coated, and the heat-generating element lead-out electrode **9** formed on the heat-generating element **7** through the insulating member **8** are disposed between the blowout section **11e** and the front surface **4a** of the insulating substrate **4**.

The heat-generating element **7** is formed of a high-resistance conductive material that has comparatively high resistance and generates heat with electrical conduction provided thereto. Examples of the high-resistance conductive material include materials containing nichrome, V, Mo, and Ru. The heat-generating element **7** can be formed by, for example, a method of forming a pattern with a substance in a paste obtained by mixing the above-described high-resistance conductive material, a resin binder, and the like, on the front surface **4a** of the insulating substrate **4** using a screen printing technique and baking the pattern.

The insulating member **8** is formed of an insulating material, such as glass. The heat-generating element lead-out electrode **9** is disposed to face the heat-generating element **7** through the insulating member **8**. With this, the heat-generating element **7** is superimposed on the blowout

section 11e of the fuse element 11 through the insulating member 8 and the heat-generating element lead-out electrode 9. With such a superimposed structure, it is possible to allow heat generated by the heat-generating element 7 to be efficiently transmitted to the blowout section 11e.

Even in the protection device 30 of the embodiment, similarly to the fuse device 20 of the second embodiment, as shown in FIG. 5(c), a width 1d of the blowout section 11e in a plan view has a length ($\{1d/2d\} \times 100 \geq 80\%$ (%)) equal to or greater than 80% of a width 2d of each of joining portions joining the first electrode 2a and the second electrode 2b to the blowout section 11e, is preferably a length equal to or greater than 95% of the width 2d of each of the joining portions, and more preferably exceeds 100% of the width 2d of each of the joining portions.

Similarly to the fuse device 20 of the second embodiment, as shown in FIG. 5(b), a cover member 5 is preferably attached to the protection device 30 of the embodiment through an adhesive. As a material of the cover member 5, the same material as in the fuse device 20 of the second embodiment can be used.

As shown in FIG. 5(a), the first electrode 2a and the second electrode 2b are disposed in a pair of facing end portions on the front surface 4a of the insulating substrate 4. The first heat-generating element electrode 9a and the second heat-generating element electrode 9b are disposed in another pair of facing end portions on the front surface 4a of the insulating substrate 4.

Each of the first electrode 2a, the second electrode 2b, the first heat-generating element electrode 9a, the second heat-generating element electrode 9b, and the heat-generating element lead-out electrode 9 is formed with a conductive pattern of Ag wiring, Cu wiring, or the like.

Each of the first electrode 2a, the second electrode 2b, the first heat-generating element electrode 9a, the second heat-generating element electrode 9b, and the heat-generating element lead-out electrode 9 may be coated with an electrode protection layer to suppress changes in electrode characteristics due to oxidation or the like. As a material of the electrode protection layer, a Sn-plated film, a Ni/Au-plated film, a Ni/Pd-plated film, a Ni/Pd/Au-plated film, or the like can be used.

In the protection device 30 of the embodiment, the first electrode 2a, the second electrode 2b, and the first heat-generating element electrode 9a are electrically connected to the first external connection electrode 42a, the second external connection electrode 42b, and the heat-generating element power feed electrode 6 formed on a rear surface 4b of the insulating substrate 4 through castellations, respectively. The connection of the first electrode 2a and the first external connection electrode 42a, the connection of the second electrode 2b and the second external connection electrode 42b, and the connection of the first heat-generating element electrode 9a and the heat-generating element power feed electrode 6 may be performed through through-holes. The connection of the second heat-generating element electrode 9b and the heat-generating element lead-out electrode 9 can be performed by a known method, such as one using a through-hole (not shown).

In the protection device 30 of the embodiment, an electrical conduction path to the heat-generating element power feed electrode 6, the first heat-generating element electrode 9a, the heat-generating element 7, the second heat-generating element electrode 9b, the heat-generating element lead-out electrode 9, and the blowout section 11e of the fuse element 11, and an electrical conduction path to the first external connection electrode 42a, the first electrode 2a, the

blowout section 11e, the second electrode 2b, and the second external connection electrode 42b are formed.

The protection device 30 of the embodiment is mounted on a current path of a circuit board (not shown) through the first external connection electrode 42a, the second external connection electrode 42b, and the heat-generating element power feed electrode 6 for use. With this, for example, the blowout section 11e of the protection device 30 is connected to the current path of the circuit board through the first external connection electrode 42a and the second external connection electrode 42b, and the heat-generating element 7 is connected to a current control device provided on the circuit board through the heat-generating element power feed electrode 6.

In the protection device 30 of the embodiment, in a case where an abnormality occurs in the circuit board, electrical conduction is provided to the heat-generating element 7 through the heat-generating element power feed electrode 6 by the current control device provided on the circuit board. With this, the heat-generating element 7 generates heat, the blowout section 11e is heated through the insulating member 8 and the heat-generating element lead-out electrode 9, and the blowout section 11e is blown out. With this, the first electrode 2a and the second electrode 2b are disconnected, and the current path of the circuit board is cut off.

In a case where the blowout section 11e is formed in such a manner that a low-melting-point metal layer 1a and high-melting-point metal layer 1b are laminated in a thickness direction, and in a case where electrical conduction is provided to the heat-generating element 7 by the current control device provided on the circuit board, the low-melting-point metal layer 1a of the blowout section 11e is heated and melted, the high-melting-point metal layer 1b is dissolved by a generated molten material of the low-melting-point metal layer 1a, and the blowout section 11e is quickly blown out.

Similarly to the fuse device 20 of the second embodiment, the protection device 30 of the embodiment in which the width 1d of the blowout section 11e is the length equal to or greater than 80% of the width 2d of each of the joining portions joining the first electrode 2a and the second electrode 2b to the blowout section 11e has the blowout section 11e that has the large width 1d and low resistance, and can thus contribute to an increase in rated current.

In a case where a blowout temperature of the blowout section 11e in the protection device 30 of the embodiment is equal to or lower than 400°C., the first electrode 2a and the second electrode 2b can be restrained from reaching a high temperature at the time of blowout and adversely influencing a member connected to the first electrode 2a and the second electrode 2b, and the circuit board to which the first external connection electrode 42a and the second external connection electrode 42b are connected. Accordingly, the length of the blowout section 11e (the distance between the first electrode 2a and the second electrode 2b) can be reduced, the size of the protection device 30, and a rated current can be further increased, compared to a case where the blowout temperature of the blowout section 11e exceeds 400°C.

FIG. 6(a) is a plan view showing a protection device of a sixth embodiment. FIG. 6(b) is a side view of the protection device shown in FIG. 6(a) from a lower side of FIG. 6(a). FIG. 6(c) is a side view of the protection device shown in FIG. 6(a) from a right side of FIG. 6(a). FIGS. 6(a) and 6(c)

show a state in which a cover member **5** of a protection device **60** shown in FIG. 6(b) is removed.

As shown in FIGS. 6(a) to 6(c), the protection device **60** includes a fuse element **11**, a heat-generating element **17** that heats the fuse element **11** to be blown out, an insulating substrate **4**, and a first electrode **2a** and a second electrode **2b** disposed on a front surface **4a** of the insulating substrate **4**. In the protection device **60** of the embodiment, as shown in FIG. 6(b), the fuse element **11** is disposed across the first electrode **2a** and the second electrode **2b**. That is, the fuse element **11** spans from the first electrode **2a** to the second electrode **2b**. Each of the first electrode **2a** and the second electrode **2b** functions as a terminal that is conductively connected to the fuse element **11**. The protection device **60** of the embodiment has a heat-generating element lead-out electrode **19** that is connected to the heat-generating element **17**.

A difference between the protection device **60** of the sixth embodiment and the protection device **30** of the fifth embodiment is only the shape of the blowout section **11e**, the disposition of the heat-generating element **17** and an insulating member **18**, and the disposition of wiring connected to the heat-generating element **17**. Accordingly, in the sixth embodiment, only the difference from the fifth embodiment will be described, and the same members as those in the fifth embodiment are represented by the same reference numerals and description thereof will not be repeated.

In the protection device **60** of the embodiment, unlike the protection device **30** of the fifth embodiment, as shown in FIG. 6(b), side surfaces of the blowout section **11e** in a direction connecting the first electrode **2a** and the second electrode **2b** are in rectangular shapes in sectional view. That is, the shapes of surfaces in a direction substantially perpendicular to the direction connecting the first electrode **2a** and the second electrode **2b** among surfaces of the blowout section **11e** are rectangular shapes. Then, a heat-generating element lead-out electrode **19** is disposed between the blowout section **11e** and the front surface **4a** of the insulating substrate **4**. The heat-generating element **17** and the insulating member **18** with which the heat-generating element **17** is coated are disposed on a rear surface **4b** of the insulating substrate **4**.

The heat-generating element lead-out electrode **19** is disposed to face the heat-generating element **17** through the insulating substrate **4**. With this, the heat-generating element **17** is superimposed on the blowout section **11e** of the fuse element **11** through the insulating substrate **4** and the heat-generating element lead-out electrode **19**. With such a superimposed structure, it is possible to allow heat generated by the heat-generating element **17** to be efficiently transmitted to the blowout section **11e**.

In the protection device **60** of the embodiment, similarly to the protection device **30** of the fifth embodiment, as shown in FIG. 6(c), a width **1d** of the blowout section **11e** in a plan view has a length ($\{1d/2d\} \times 100 \geq 80\%$) equal to or greater than 80% of a width **2d** of each of joining portions joining the first electrode **2a** and the second electrode **2b** to the blowout section **11e**, is preferably a length equal to or greater than 95% of the width **2d** of each of the joining portions, and more preferably exceeds 100% of the width **2d** of each of the joining portions.

In the protection device **60** of the embodiment, in a case where an abnormality occurs in the circuit board, electrical conduction is provided to the heat-generating element **17** by a current control device provided on the circuit board. With this, the heat-generating element **17** generates heat, the blowout section **11e** is heated through the insulating sub-

strate **4** and the heat-generating element lead-out electrode **19**, and the blowout section **11e** is blown out. With this, the first electrode **2a** and the second electrode **2b** are disconnected, and the current path of the circuit board is cut off.

In a case where the blowout section **11e** is formed in such a manner that a low-melting-point metal layer **1a** and high-melting-point metal layer **1b** are laminated in a thickness direction, and in a case where electrical conduction is provided to the heat-generating element **17** by the current control device provided on the circuit board, the low-melting-point metal layer **1a** of the blowout section **11e** is heated and melted, the high-melting-point metal layer **1b** is dissolved by a generated molten material of the low-melting-point metal layer **1a**, and the blowout section **11e** is quickly blown out.

Similarly to the protection device **30** of the fifth embodiment, the protection device **60** of the embodiment in which the width **1d** of the blowout section **11e** is the length equal to or greater than 80% of the width **2d** of each of the joining portions joining the first electrode **2a** and the second electrode **2b** to the blowout section **11e** has the blowout section **11e** that has the large width **1d** and low resistance, and can thus contribute to an increase in rated current.

In a case where a blowout temperature of the blowout section **11e** in the protection device **60** of the embodiment is equal to or lower than 400°C., the first electrode **2a** and the second electrode **2b** can be restrained from reaching a high temperature at the time of blowout and adversely influencing a member connected to the first electrode **2a** and the second electrode **2b**, and the circuit board to which the first external connection electrode **42a** and the second external connection electrode **42b** are connected. Accordingly, the length of the blowout section **11e** (the distance between the first electrode **2a** and the second electrode **2b**) can be reduced, to reduce the size of the protection device **60**, and the rated current can be further increased, compared to a case where the blowout temperature of the blowout section **11e** exceeds 400°C.

What is claimed is:

1. A fuse device comprising:
an insulating substrate;
a first electrode and a second electrode provided on a front surface of the insulating substrate;
a fuse element;
a heat-generating element provided on the front surface or a rear surface of the insulating substrate;
an insulating material covering the heat-generating element;
a heat-generating element lead-out electrode electrically connected with the fuse element and disposed to face the heat-generating element; and
a cover member provided on the insulating substrate and covering the fuse element; wherein,
the fuse element comprises a flat plate-shaped blowout section with no through-hole disposed between the first electrode and the second electrode, wherein a length of a width of the flat plate-shaped blowout section has a length greater than 100% and equal to or less than 200% of a length of a width of each of joining portions joining the first electrode and the second electrode to the flat plate-shaped blowout section;
the fuse element is composed of a low melting-point metal layer and a high melting-point metal layer laminated on both surfaces of the low melting-point metal layer;
a side surface of the fuse element which is joined to the first electrode and a side surface of the fuse element which is joined to the second electrode are coated with the high melting-point metal layer;
side surfaces of the fuse element in a direction connecting the first electrode and the second electrode are not coated with the high melting-point metal layer, wherein the low melting-point metal layer is exposed on the side surfaces of the fuse element in the direction connecting the first electrode and the second electrode;
the fuse element is connected to the first electrode and the second electrode via solder;
leakage of the low melting-point metal layer from the side surface to a junction of the fuse element and the first electrode and to a junction of the fuse element and the second electrode does not occur;
inflow of the solder to the low melting-point metal layer does not occur;
the heat-generating element and the heat-generating element lead-out electrode are electrically connected; and
the low melting-point metal layer and the solder provided between the fuse element and the first electrode is not in direct physical contact and the low melting point metal layer and the solder provided between the fuse element and the second electrode is not in direct physical contact.
2. The fuse device according to claim 1, wherein a blowout temperature of the flat plate-shaped blowout section is 140° C. to 400° C.

3. The fuse device according to claim 1, wherein the low melting-point metal layer is composed of Sn or an alloy containing Sn as a primary constituent, and wherein the high melting-point metal layer is composed of any one selected from Ag, Cu, an alloy containing Ag as a primary constituent, and an alloy containing Cu as a primary constituent.
4. The fuse device according to claim 3, wherein a ratio of a total thickness of the low melting-point metal layer to a total thickness of the high melting-point metal layer is 1:1 to 50:1.
5. The fuse device according to claim 1, wherein the flat plate-shaped blowout section is joined to the first electrode and the second electrode by the solder.
6. A protection device comprising:
the fuse device according to claim 1, wherein the fuse element is disposed across the first electrode and the second electrode.
7. The fuse device according to claim 1, wherein the flat plate-shaped blowout section and the insulating substrate are configured with a space formed between the flat plate-shaped blowout section and the front surface of the insulating substrate.
8. The fuse device according to claim 1, wherein the first electrode and the second electrode are each coated with an electrode protection layer which is any one of a group consisting of a Sn-plated film, a Ni/Au-plated film, a Ni/Pd-plated film, and a Ni/Pd/Au-plated film.
9. The fuse device according to claim 1, further comprising:
a first external connection electrode and a second external connection electrode on the rear surface of the insulating substrate; and
a first castellation and a second castellation on a side surface of the insulating substrate, wherein the first external connection electrode and the first electrode is connected via the first castellation, and the second external connection electrode and the second electrode is connected via the second castellation.
10. The fuse device according to claim 1, wherein the heat-generating element is provided on the front surface, wherein the heat-generating element lead-out electrode is formed on the insulating material, wherein the fuse element and the heat-generating element lead-out electrode are electrically connected, and wherein the flat plate-shaped blowout section of the fuse element is superimposed on the heat-generating element through the insulating material and the heat-generating element lead-out electrode.
11. The fuse device according to claim 1, wherein the heat-generating element is provided on the rear surface, wherein the heat-generating element lead-out electrode is provided on the front surface, and the fuse element and the heat-generating element lead-out electrode are electrically connected, and wherein the flat plate-shaped blowout section of the fuse element is superimposed on the heat-generating element through the insulating substrate and the heat-generating element lead-out electrode.
